METHOD OF AND APPARATUS FOR PREPARING PRINTING SURFACES

Ernest S. Ballard, Berkeley, Calif.

Application February 25, 1935, Serial No. 8,197

20 Claims. (Cl. 101—401.1)

The present invention relates to the preparation of printing surfaces and more particularly to novel methods of and apparatus for accurately reproducing an image on a printing surface whereby designs may be transferred accurately and without distortion from a master cylinder to cylinders to be etched for textile, wall paper and other intaglio printing purposes.

Prior to my present invention it has been impossible to effect an accurate transfer by offset printing methods of a continuous image or design from the surface of a master cylinder to the surface of a second cylinder with sufficient accuracy to provide an intaglio printing surface. The prior methods and apparatus used in offset printing for the transfer of images from one cylinder to another fail to transfer the image sufficiently accurately for intaglio printing of continuous images since they do not preserve the image in its original form during transfer operations and do not match the edges of the transferred images.

In the prior art offset printing transfer methods, direct transfer by rolling contact is used from the master cylinder to a rubber transfer cylinder from which the image is transferred to the printing cylinder by revolving contact of the transfer and printing cylinders. As the length of the image on the master surface cannot in practice be made exactly the same as the cylinder to which the image is to be transferred, since very slight differences in diameter are sufficient to destroy the transfer accuracy for intaglio purposes, and very slight slippage with cylinders of exactly the same size will also destroy the accuracy of the image, the prior transferred images are distorted and fail to meet accurately at the edges and are not continuous. Efforts to secure accurate meeting of the edges of the designs transferred by the prior art methods have been made by introducing slippage between the surfaces during transfer of a design. Efforts have also been made to use the prior art offset printing methods and apparatus to overcome the inaccuracy in the meeting of the edges of the transferred designs in order that they may be used for intaglio printing, transferring the designs to a rubber blanket by rolling contact, and thereafter attempting by painful hand work to stretch the blanket to conform in length with the circumference of the intaglio cylinder to which the image is to be transferred.

It will be appreciated that these prior efforts involving slippage between surfaces as transfer is effected or the stretching of a transfer element

are not adapted to any but very crude intaglio printing work, if acceptable at all, and both methods result in material distortion of the images during the transfer operations. The prior methods of transfer of images have therefore been applied only to offset printing, and can not be successfully used for the transfer of half tone and like designs from a master cylinder to cylinders to be etched for high grade and accurate intaglio printing reproduction of continuous images.

The methods and apparatus of the present invention successfully overcome the two major difficulties of the prior art pointed out above and provide for perfect transfer of images or designs of whatever nature and under all conditions, whereby the offset method of transfer may for the first time be commercially applied to the production of accurately etched high grade intaglio printing cylinders having continuous images, as well as for high grade lithograph and other printing of continuous images.

Accordingly it is a primary object of the present invention to provide a novel method and novel apparatus for effecting accurate transfer of an image without distortion, slurring or degrading of tone values from one surface to another, whereby the surface which finally receives the image or design is ready for use as a printing surface or is ready for further preparation such as etching to provide an intaglio or other kind of printing surface.

A further object of the present invention is to provide a method and apparatus for effecting accurate transfer of images or designs from a surface bearing the desired image or design to another surface to be used for printing purposes, involving the use of an expansible elastic member to accomplish an intermediate step in the transfer process.

Another object of the present invention is to provide a method involving as a step the novel procedure of transferring a design to or from the surface of a rigid member by employing the surface of an elastic member to effect the transfer by direct uniform contact.

A still further and major object of the present invention is to provide for the first time a method and apparatus for effecting accurate transfer of a continuous image or design from the peripheral surface of a master cylinder to the surface of a secondary cylinder of the same or slightly different size. This I accomplish by direct and uniform contact with the concave cylindrical surface of an expansible element.

Still another object of the present invention is to provide a novel apparatus whereby the image transfer methods disclosed herein may be readily and effectively carried out.

5 A still further object of the present invention is to provide an apparatus to be employed in the transfer of images or designs, the said apparatus comprising expandible means having a surface adapted to be brought into uniform contact with the surface of a rigid member whereby the two surfaces will be coextensive with each other during the time of contact between them.

10 Other and more specific objects of the present invention will appear in the following disclosure 15 of a preferred embodiment of my invention and from the terms of the appended claims.

15 Referring to the drawing in which like reference characters indicate like parts:

20 Figure 1 is a view in longitudinal section through an apparatus diagrammatically illustrated for carrying out image transfer operations in accordance with my invention.

25 Figure 2 is an end view of the form of apparatus shown in Figure 1.

30 Figure 3 is a more or less diagrammatic illustration of essential apparatus for carrying out the steps of the preferred method of transferring images or designs.

35 Figure 4 is a view similar to Figure 3 illustrating the apparatus in another stage of its operation.

40 Figure 5 is a view in elevation of a portion of the apparatus illustrated in Figures 3 and 4.

45 In the description which is to follow, it will be understood that the term "image" applies to any figure or design comprised of lines or a pattern of half tone dots formed in or on the surface of a member, for example, a master cylinder, by a photographic process or by hand or machine tracing or engraving. While the embodiment selected for purposes of illustration discloses a process and apparatus for effecting transfer of a continuous image or design from a master cylinder to a cylindrical printing form, it will be understood that the invention is not limited to transfer of images under these conditions. Also it will be understood that transfer of the image to the printing form may be in ink, asphaltum, lacquer or any other transfer medium capable of resisting mordants whereby the resulting transferred image will be acid resisting for the purpose of etching. The image transferred to the printing form may also be used for lithographic or other offset printing or may be etched in intaglio.

55 Referring now to the drawing in which Figures 3 and 4 illustrate the preferred method of conveying or transferring an image from the surface of one cylinder to another, the numeral 10 indicates an intermediate transfer means which is illustrated more in detail in Figures 1 and 2. The transfer means 10 is a very important feature of my present invention and comprises a member 14 of generally tubular form which is composed of rubber or a like elastic and expandible material. The member 14 is provided with annular extensions 16 of decreased thickness which are more flexible and yielding than the main body portion and the decrease in thickness provides guide shoulders 17 at each end of the main body portion. The member 14 is mounted in a holder comprising a member 18 preferably of metal which is capable of withstanding fluid pressure applied against its interior wall. In the embodiment shown, the member 14 is concentrically mounted in the member 18 which is of cylindrical

form for convenience. The inner wall of the cylinder 18 is spaced from the outer peripheral surface of the member 14 to provide an annular chamber 19 which is concentric with the member 14 and the cylinder 18. A suitable conduit connection 21 adapted to be placed in communication both with a source of fluid pressure and of negative gauge pressure, as demanded by transfer operations, is carried by the cylinder 18 and communicates with the chamber 19.

10 The annular extensions 16 serve to secure the flexible body 14 concentrically in position in the cylinder 18 and this is accomplished by rings 22 and 23 between which each of extensions 16 are secured. The rings 22 and 23 form a fluid tight 15 seal at each end of the device 10 and the entire assembly is held in place by means of cover plates 24 and 26. Suitable securing means such as studs 27 are circumferentially spaced about the ends of the member 10 and serve to secure 20 the cover plates in position.

25 From the foregoing description of the intermediate transfer device it will be seen that as a suction or negative gauge pressure is applied within the chamber 19, the body portion of the member 14 will expand as shown in Figure 4 causing its inner concave surface to increase in diameter. It should be noted that this diametrical increase is the result of a uniform radial expansion occurring throughout the entire length of 30 the main body portion of the member 14. When fluid pressure is applied to the chamber 19, the body portion of the member 14 will contract as shown in Figure 3 and this contraction, being uniform throughout the length of the member 35 14, its inner surface will move radially and in a uniform manner. During expansion and contraction of the member 14, the extensions 16 flex as shown in Figures 3 and 4 of the drawing and the radially extending faces 17 serve as guides 40 in cooperation with the inner faces of the rings 23.

45 Expansion and contraction of the member 14 may be effected by mechanical means rather than by the hydraulic or pneumatic means disclosed, however, I prefer to employ hydraulic or 50 pneumatic means.

55 In carrying out my process of transferring an image from one surface to another I preferably mount the intermediate transfer means or device 10 just described in holders 28 (Figure 5) which 50 are secured to a sliding base 29 which is slidable on wings or guides 30 formed on a bed plate or like base member 31. The holders 28 are or may be adjustable to accommodate the device 10 in different sizes or a series of holders 28 of as 55 sorted sizes may be provided. As illustrated, each holder 28 may comprise a pedestal having branching arms 32 which form a cradle 33 within which the device 10 rests. A clamp 34 fits over the device 10 as it rests in the arms 32 and is 60 clamped over the device 10 and to the arms 32 by means of bolts 36.

65 The cylinder 38 which may be a master cylinder bearing the design to be transferred or a printing form adapted to receive the design is mounted on an arbor or shaft 39 between centers formed on the bar 41 and the axially adjustable bar 42. The bars 41 and 42 are carried by pedestals 43 and 44 respectively, which are secured to the base 45. Axial adjustment of the bar 42 is provided 70 for by having threads formed thereon which engage within a threaded hole in the pedestal 44. A hand wheel 46 provides for turning the bar 42 within the pedestal whereby it may be moved axially in either direction to clamp or release 75

the shaft or arbor 38. Equivalent means in place of the rests or pedestals 28 and the bars 41 and 42 may be used to hold the transfer device 10 and the cylinder 38 concentric during the transfer operation, the devices described being illustrative of means in one form for carrying out my invention.

In operation of the apparatus to effect transfer of images by the methods disclosed herein, a master cylinder bearing the design in any one of the coating or transfer mediums previously referred to is secured to a suitable arbor 38, or if it is already mounted on a shaft, the said shaft or arbor is clamped between the centers on the rods 41 and 42. During this operation the intermediate transfer device 10 occupies the position illustrated in Figure 4 of the drawing. The rubber member 14 is expanded by placing the conduit connection 21 in communication with a source of vacuum which exhausts the air from the annular chamber 19 causing the body portion of the member 14 to expand whereby its internal diameter is increased until it is slightly larger than the external diameter of the cylinder 38. While the mere lowering of the pressure in the annular chamber will accomplish contraction of the member 14, I find that if the space is filled with a liquid such as water, one stroke of a pump operating in the water-filled circuit will distend the member 14 and this action is more decisive and the expansion more uniform. The circuit is preferably so arranged that when the water is withdrawn a vacuum is created in chamber 19. The device 10 is next moved to the left as viewed on the drawing to the position illustrated in Figure 3 so that the member 14 surrounds the cylinder 38. It will be understood that negative gauge pressure or a vacuum is maintained in the chamber 19 so as to keep the concave surface of the member 14 spaced from the surface of the cylinder 38 to avoid blurring of the image.

With the cylinder 38 in position within the device 10, water or fluid under pressure is forced into chamber 19. The fluid with a suitable source of fluid under pressure is relatively heavy and is preferably in the neighborhood of three hundred pounds per square inch. Also a liquid is preferably employed to exert this pressure. The member 14 is thereby forced to contract radially at all points so that it presses upon the surface of the cylinder 38 with a uniform pressure and without slippage of the surfaces at any point of contact. This uniform pressure results in an accurate transfer of the image on the surface of the cylinder 38 to the concave surface of the member 14. As the surfaces of the cylinder 38 and the member 14 are exactly coextensive when they are in contact and as contact occurs at all points simultaneously the transfer is effected without distortion. That is to say all of the elements of the design bear the same relationship to each other after transfer is effected as in the original design provided on the cylinder 38. This undistorted relationship of the component parts of the design continues during subsequent uniform expansion of the member 14 which is accomplished by release of pressure and again exhausting the air from the annular chamber 19. With the rubber cylinder in the distended position, the member 10 is moved to the right as viewed in the drawing permitting the cylinder 38 to be removed.

The image which now exists by transfer on the rubber member 14 may be transferred to a

blank printing form which is substituted for the master cylinder 38. This is accomplished by substantially repeating the steps of the operation described above, namely shifting the member 10 to the left and releasing the vacuum and applying fluid pressure within the chamber 19. Immediate transfer of the image on the surface of the member 14 to the blank surface of the printing cylinder occurs and this transfer is accomplished without distortion for the reasons set forth above. Removal of the printing cylinder is accomplished by releasing pressure within the chamber 19, again exhausting the air or fluid from the said chamber, shifting holder 28 to the position shown in Figure 4 and removing the form.

As soon as the transfer medium has dried or been properly treated to make it more resistant, the surface of the printing cylinder can be etched for printing or if a transfer medium suitable for the purpose is employed, the printing cylinder can be used directly for lithographic printing.

It is to be especially noted that the transfer method described is particularly adapted for the transfer of designs which are continuous about the surface of the master cylinder 38 and in fact it is the only known method by which transfer of continuous designs can be successfully accomplished that are suitable for use in commercial intaglio wall paper, textile, and like printing operations. Such designs must not overlap at their ends nor have their edges spaced apart by even a very slight amount when they are transferred to a printing cylinder or other printing member which is circular in cross section, and there must be no distortion of the transferred image. The uniform contraction of the rubber tube and simultaneous contact established between the surface of the rubber tube and the master cylinder and the rubber tube and the printing cylinder makes it possible to transfer the continuous unbroken image from one cylinder to another without distortion of the image parts with relation to each other. It should also be noted in this connection that transfer of continuous images may be effected perfectly even though the cylinder from which the transfer is made is slightly larger or smaller in diameter than the cylinder which is to receive the transferred image. This is important in color printing where perfect register of superimposed images is necessary. By employing the methods of the present invention, the several master color cylinders may lack uniformity as to circumference, but the transferred images if conveyed to cylinders of the same diameter will register perfectly in printing. Any necessary adjustment takes place automatically in the contraction or expansion of the rubber cylinder. This adjustment occurs when the rubber cylinder contracts upon the exterior surface of a cylinder of fixed diameter and at the instant that this adjustment is effected, the transfer takes place by contact, and the adjustment halts at the moment transfer by contact begins.

From the foregoing description of the methods and apparatus of the present invention it will be seen that they are adapted for use generally where transfer operations are to be carried out and also that transfer operations which were heretofore impossible can be readily accomplished.

The invention may be embodied in other specific forms without departing from the spirit or essential characteristics thereof. The present embodiments are therefore to be considered in

all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A method of preparing a printing surface by use of an apparatus embodying an elastic transfer member which comprises the steps of applying a transfer coating on a master surface bearing the desired image, bringing the surface of the elastic transfer member into contact with said master surface by the direct application of fluid pressure thereto to cause a uniform simultaneous transfer of said entire coating to the surface of said elastic member, separating said surfaces and thereafter bringing the surface of said elastic member carrying the transferred image into contact with the surface to be prepared by the direct application of fluid pressure thereto to cause the uniform simultaneous transfer of said coating substance to said printing surface.
2. The method of preparing a printing surface for etching by use of apparatus embodying an elastic transfer member which comprises the steps of applying a mordant resisting transfer coating to the printing areas of an image on a master surface bearing the image to be reproduced on said printing surface, bringing the surface of an elastic member into contact with said master surface, separating said surfaces and transferring said coating thereto, and thereafter bringing the coated surface of said elastic member into contact with the surface to be prepared for etching, said first and second transfer steps being accomplished by the application of fluid pressure to said elastic member normal to said surfaces and uniform at all points of said surfaces in contact, thereby causing an accurate simultaneous transfer of said coating substance to the surface to be etched.
3. The method of transferring an image from a surface bearing the image to the surface of a printing member comprising the steps of first transferring the image from said first named surface to the surface of an elastic member, and thereafter transferring the image reproduced on said elastic member to the surface of a printing member, said transfer steps being carried out by inflating said elastic member so that its surface approaches and comes into intimate contact with each of said surfaces in turn.
4. The method of preparing a series of printing cylinders all of the same diameter for printing superimposed images in accurate register, comprising the steps of producing an image on each one of a series of master cylinders of substantially the same or different diameters, transferring the image on one master cylinder to a self adjusting transfer surface and thereafter transferring the image formed on said self adjusting surface to the surface of one of said printing cylinders by simultaneous application of all points on said surface to the surface of one of said printing cylinders, said transfer operation being repeated for each master cylinder and its corresponding printing cylinder.
5. An apparatus for effecting transfer of an image from one printing surface to another comprising an expansible and contractible member having a concave cylindrical surface and means to cause said concave cylindrical surface to assume different diameters.
6. An apparatus for effecting transfer of an image from one printing surface to another, comprising an expansible and contractible member having a concave cylindrical surface adapted to be brought into contact with the surface of a printing cylinder or the like to effect transfer of an image to or from the said concave cylindrical surface, and means to cause said concave cylindrical surface to approach the surface of said printing cylinder and to cause simultaneous contact of said surfaces at all points.
7. In an apparatus for transferring images from one surface to another, an elastic transfer member, said member having a concave cylindrical surface capable of assuming different internal diameters as said member expands and contracts.
8. An elastic transfer member of annular form, comprising a body portion and sleeve-like extensions at each end of said body portion adapted to be secured in mounting means for said member, said extensions being of less thickness and greater flexibility than said body portion.
9. An apparatus for effecting transfer of an image from one printing surface to another comprising a transfer device having a concave cylindrical transfer surface, means to cause said surface to assume different internal diameters, means to secure a printing cylinder or the like with its surface in concentric relationship to said concave surface, and means for axially separating said cylinder and said transfer device.
10. A transfer device comprising a rigid hollow member, an elastic transfer member of sleeve-like form secured in said hollow member and spaced from the interior of said hollow member to provide a chamber, and means for varying the pressure in said chamber to cause expansion and contraction of said elastic member.
11. Apparatus to be employed in the transfer of continuous images or designs, comprising a cylinder of rubber secured in a backing of such size with respect to the rubber cylinder that an annular space is provided between the external peripheral surface of the rubber cylinder and the backing, the said space providing for application of fluid pressures at above or below atmospheric pressure to effect radial movement of all points of the concave interior surface of the rubber cylinder toward and from its center.
12. A cylindrical rubber member to be employed in the transfer of images or designs generally of sleeve-like form shaped to encircle a master cylinder or a printing cylinder and having axial guide shoulders and axially extending flexible clamping portions extending beyond said guide shoulders.
13. A method of preparing a printing surface by use of an apparatus embodying a surface to be prepared and a master surface of convex shape formed on members which are circular in cross section and embodying an elastic transfer member adapted to encircle said surfaces in turn and approach said surfaces solely by radial movement of all points on its surface which comprises the steps of applying a transfer coating on the master surface bearing the desired image, bringing the surface of the elastic transfer member into contact with said master surface to cause a uniform simultaneous transfer of said entire coating to the surface of said elastic member, separating said surfaces and thereafter bringing the surface of said elastic member carrying the transferred image into contact with the surface to be prepared to cause the uniform simultaneous transfer of said coating substance to said printing surface.

14. The method of preparing a printing surface for etching by use of apparatus embodying a printing surface and a master surface of convex shape formed on members which are circular in cross section and embodying an elastic member provided with a concave surface adapted to approach said surfaces in turn solely by radial movement of all points on the concave surface comprising the steps of applying a mordant resisting transfer coating to the printing areas of an image on said master surface bearing the image to be reproduced on said printing surface, bringing the surface of said elastic member into contact with said master surface, separating said surfaces and transferring said coating thereto, and thereafter bringing the coated surface of said elastic member into contact with the surface to be prepared for etching, said first and second transfer steps being accomplished by the application of pressure to said elastic member normal to said surfaces and uniform at all points of said surfaces in contact, thereby causing an accurate simultaneous transfer of said coating substance to the surface to be etched.
15. An apparatus for effecting transfer of an image from one printing surface to another comprising a transfer device having a cylindrical transfer surface, means whereby said device may be placed in spaced concentric relation with a printing surface, and means to vary the diameter of said transfer surface to contact the same with said printing surface.
16. An apparatus for effecting transfer of an image from one printing surface to another comprising means to support a printing surface, means to support a transfer device in predetermined relation thereto, said device comprising a cylindrical transfer surface, guide means whereby said transfer surface may be placed in pre-
- determined spaced concentric relation to said printing surface, and means to vary the diameter of said transfer surface to contact the same with said printing surface.
17. The method of transferring a surface image to another surface from a member having a deformable wall of sufficient rigidity to normally have a definite conformation, comprising the steps of arranging the deformable wall substantially in parallelism with said surface that is to receive the image, and applying pressure fluid directly against said wall to deform it into full and uniform contact with said surface.
18. The method of transferring an image from the surface of one member to the surface of another where one of the members is flexible, comprising the steps of arranging said surfaces in proximity while subjecting the flexible member to vacuum to maintain the surfaces in separation, and thereafter destroying the vacuum and bringing said surfaces into full intimate contact.
19. In combination, an assembly of parts for effecting the transfer of printing images, said assembly comprising an image bearing member, a transfer member having a flexible wall of rather definite inherent shape normally spaced slightly from the image of the first mentioned member when assembled, and means for applying fluid pressure to said wall to urge it into uniform surface contact with said image.
20. In apparatus of the character described, a pressure-responsive wall having a surface adapted to carry an image, a support for said wall, flexible means for mounting said wall on said support and for guiding said wall during its pressure-responsive movements, and means for applying fluid pressure to said wall.

ERNEST S. BALLARD.
